UNITED STATES PATENT OFFICE.

ROBERT L. MARTIN, OF OCALA, FLORIDA.

COOKING-STOVE.

1,392,956.

Specification of Letters Patent.

Patented Oct. 11, 1921.

Application filed July 1, 1919. Serial No. 307,993.

To all whom it may concern:

Be it known that I, ROBERT L. MARTIN, a citizen of the United States, residing at Ocala, in the county of Marion and State 5 of Florida, have invented new and useful Improvements in Cooking-Stoves, of which the following is a specification.

My present invention relates to improvements in cooking stoves and the primary object is to provide a novel and improved stove which is capable of being used satisfactorily for cooking food while the exhaust gases from an internal combustion engine are employed as the source of heat.

According to the present invention, the hot exhaust gases from the engine are caused to pass through a closed coil or other suitable form of piping contained within the stove so that the heat is absorbed from such gases 20 through the walls of the coil or piping, and hence the gases or soot accompanying them cannot reach the cooking chamber of the stove to either contaminate the food or to smut or blacken the cooking vessels. Furthermore,

the stove is so constructed that the heat will be distributed uniformly to the cooking vessels, the heat will be retained within the stove after the hot gases have ceased to pass through the heating coil, thus continuing 30 the cooking operation after the source of heat has been cut off from the stove, and moreover, means is provided to effectively prevent spilling of the food from the cooking vessels when the stove is carried by an automobile and the cooking operation is carried on while the automobile is in transit.

To these and other ends the invention consists in certain improvements and combinations and arrangements of parts all as 40 will be hereinafter more fully described, the features of novelty being pointed out particularly in the claims at the end of the specification.

45 In the accompanying drawings:—

Figure 1 is a side elevation partly in section showing an automobile provided with an exhaust heated cooking stove constructed in accordance with the present invention.

50 Fig. 2 is a collective view showing in perspective the body or casing of the stove, the heat distributing plate and the lid or cover which serves to close the stove and also serves to retain the cooking vessels and 55 the lids in proper position within the stove.

Similar parts are designated by the same reference characters in the several views.

Cooking stoves embodying the present invention are capable of use generally where it is desirable or necessary to cook foods 60 by heat derived from the hot exhaust gases from an internal combustion engine or by an equivalent heating medium. It is particularly suitable for use upon automobile, where it is desirable to carry therewith 65 means for cooking or heating foods by heat derived from the exhaust gases of the engine of the automobile, the cooking stove provided by the present invention being capable of cooking foods satisfactorily while 70 the automobile is in transit. It is to be understood, however, that the invention is not restricted to any one particular use and it will also be understood that the invention is not restricted to the precise construction 75 shown, as the stove may be used in situations other than that shown and also constructions equivalent to the construction shown are contemplated and will be included within the scope of the claims. 80

In the present instance, 1 designates a part of the chassis of an automobile provided with a body 2 which is suitably constructed and arranged interiorly to accommodate a cooking stove. The interior construction and arrangement of the body is 85 preferably like that shown and described in my application filed of even date herewith. For convenience and economy of space, the stove constitutes a part or is constituted by 90 a part of the base 3 of one of the seats 4, although it will be understood that the stove may be constructed independently of the seats or other parts of the vehicle. 5 represents conventionally an internal combustion 95 engine of the kind commonly used for the propulsion of automobiles, the engine 5 in the instance shown serving for the propulsion of the vehicle, part of which is illustrated. 6 represents the exhaust manifold 100 which, as is used in engines of this type, is arranged to receive the burned or exhaust gases from the different cylinders of the engine, the gases being discharged from the exhaust manifold into an exhaust pipe 7 and 105 the gases may pass through this exhaust pipe, thence through a muffler 8, as is usual, and finally escape to the atmosphere. When the exhaust gases of the engine are utilized 110 to supply heat to the stove, such gases are

diverted from the main exhaust pipe 7 through a branch pipe 9 and after circulating through a coil or other heat transferring medium within the stove 10, these 5 gases return to the exhaust pipe 7 through a second branch pipe 11. A suitable valve 12 may be located at the junction of the branch pipe 9 with the exhaust pipe 7 to direct the exhaust gases from the engine 10 either to the stove or to the muffler as may be desired, this valve being preferably provided with means similar to that provided for muffler cut out valves by which it may be operated or adjusted from the floor or 15 interior of the body.

The stove consists preferably of a casing 13 which may be made of wood and of any desired shape and dimensions. The casing, however, is constructed for heat insulation 20 in order that it will retain within the cooking chamber of the stove a sufficient amount of heat to continue the cooking and operate for a prolonged period after the supply of heat to the stove has been discontinued, the 25 stove then acting, in effect, as a so-called "fireless cooker". This desired insulation of the stove casing may be attained in different ways. As shown, the casing 13 is lined interiorly with sheet asbestos 14 of suitable 30 thickness and the asbestos lining is covered interiorly with a lining of tin or other sheet metal 15. The heating coil 10, through which the exhaust gases of the engine circulate, may be constructed in different ways. 35 Preferably, and as shown, this heating device 10 is made up of a suitable number of pipes 16 arranged parallel or substantially so and lying in the same plane or on the bottom of the stove casing, the ends of the 40 pipes being connected in alternate relation by elbows or return bends 17. All joints between the pipes and the elbows are made tight in order to avoid leakage of the exhaust gases into the interior of the stove. 45 The branch pipe 9 introduces the exhaust gases into the inlet end of the coil or heating device 10 while the branch pipe 11 receives the exhaust gases after they have traversed the coil or heating device 10, these spent 50 gases being returned by the branch pipe 11 to the exhaust pipe 7. By employing a coil or heating device in the form of return bend pipes or tubes, the hot exhaust gases are compelled to follow a sinuous course of 55 considerable length affording ample opportunity for the transfer of heat from the exhaust gases to the interior of the stove or the cooking vessels contained therein. In order to distribute the heat from the coil or 60 heating device 10 evenly to the vessels containing foods to be cooked and to also provide a suitable support for the cooking vessels, a plate 18, which is preferably perforated or foraminous, is placed on top of the 65 relatively flat coil or heating device 10, this

plate providing a flat even surface for the support of the cooking vessels and it also acting to equalize the heat which it receives from the convolutions or pipes of the coil or heating device and which it transfers to the 70 cooking vessels resting thereon. The stove is also provided with a lid or cover which serves to close the top of the cooking chamber. The lid 19 as shown is preferably rabbed to fit the correspondingly shaped top 75 edge of the casing 13 so that lateral displacement of the lid is avoided and a tight joint is obtained between the lid and the casing. The lid is also preferably constructed for heat insulation, it being shown as provided 80 with a lining or covering of asbestos 20 on its under side and a sheet of tin or other sheet metal 21 covers the asbestos. When the stove is used for cooking purposes upon an automobile, it is necessary or at least desirable to hold the lids upon the vessels and to hold the vessels down upon the supporting plate 18 in order to avoid spilling of the contents of the vessels and vibration or rattling of the lids upon the vessels or the 90 vessels upon the plate 18. For this purpose the removable lid 19 of the stove is provided with a suitable number of compression springs 22 which are appropriately spaced on its under side and extend downwardly 95 therefrom, these springs being so constructed, located and proportioned that when the lid 19 is applied to the casing of the stove, the springs will bear down upon the lids of the respective vessels beneath them with a 100 pressure sufficient to retain the lids firmly on the vessels and to retain the vessels down upon the supporting plate 18.

An exhaust-heated cooking stove constructed in accordance with the present invention is capable of efficiently cooking food without possibility of contamination of the food by the poisonous and injurious constituents of the exhaust gases and also without smutting or blackening the cooking vessels by the soot carried by such exhaust gases, because the exhaust gases are confined within the coil or equivalent heating device and hence such gases cannot reach the cooking chamber or the cooking vessels therein; on the contrary, the cooking vessels are in a chamber which may contain pure air, in consequence of which the cooked food will be wholesome. Efficiency in the cooking operation is attained by passing the hot exhaust gases through a relatively long coil or conduit of flat or substantially flat form and placing the cooking vessels on a heat conducting and distributing plate which rests directly on the coil. The heat-insulating walls of the stove also increase the efficiency of the cooking operation by preventing loss of heat and, furthermore, by confining the heat within the stove, the cooking operation is prolonged for a consider- 110 115 120 125 130

able period after the supply of exhaust gases to the stove has been cut off.

What is claimed is:—

An exhaust gas heated cooking stove 5 for automobiles comprising a closed chamber to entirely inclose cooking vessels, said chamber having a movable lid to cover said chamber and to afford access to the interior thereof, a flat exhaust gas heated coil located 10 in the bottom of said chamber, a heat distributing plate resting on the top of said coil and serving as a support for the cooking

vessels, and means to bear yieldingly on the cooking vessels in said chamber to hold said vessels down on said plate and to hold said 15 plate down on the coil.

In testimony whereof I have hereunto set my hand in presence of two subscribing witnesses.

ROBERT L. MARTIN.
